(57) CLAIM

The ornamental design for an article of jewelry, as shown and described.

DESCRIPTION

FIG. 1 is a top front perspective view of a first embodiment of an article of jewelry showing my new design;

FIG. 2 is a bottom rear perspective view thereof;

FIG. 3 is a front view, the rear view being a mirror image thereof;

FIG. 4 is a right side view, the left side view being a mirror image thereof;

FIG. 5 is a top view thereof;

FIG. 6 is a bottom view thereof;

FIG. 7 is a top front perspective view of a second embodiment of the article of jewelry showing my new design;

FIG. 8 is a front view thereof;

FIG. 9 is a rear view thereof;

FIG. 10 is a right side view thereof;

FIG. 11 is a left side view thereof;

FIG. 12 is a top view thereof; and,

FIG. 13 is a bottom view thereof.

The broken lines in FIGS. 1-6 represent portions of the article of jewelry that form no part of the claimed design.

1 Claim, 8 Drawing Sheets(56)
